FIRE CONTROL COMPUTER

Shierfield G. Myers, Freeport, and Earl W. Chafee, Brooklyn, N. Y., assignors to Sperry Gyroscope Company, Inc., Brooklyn, N. Y., a corporation of New York

Application February 11, 1933, Serial No. 656,381

13 Claims. (Cl. 235—61.5)

This invention relates to a universal computing device for the control of long range gun fire, especially where a pair or pairs of spaced base stations may be employed for sighting on the target. Our device hence is especially adapted for seacoast batteries. One object of the invention is to make such a device as complete as possible so that the graphical layout of the problem by hand on the plotting board is eliminated. Another object is to so construct such a device that it may be used with different pairs of sighting devices connected with the same battery simply by changing a few settings on the machine. A third object of the invention is to improve the reliability of such devices so that if one method of receiving data or one base station is crippled, another method or pair of base stations can be substituted in the machine without delay.

Referring to the drawings showing one form our invention may assume.

Figs. 1A, 1B, 1C and 1D represent successive parts of a complete diagrammatic layout of our invention, the parts being separated along the marginal dot and dash lines.

Fig. 2 is a bottom plan view of one of the angle resolving mechanisms by which a sine or cosine function of one of the angles used is combined with another known factor to derive an unknown factor.

Fig. 3 is a sectional detail of the same.

Fig. 4 is another sectional detail taken approximately on line 4—4 of Fig. 2.

Fig. 5 is a bottom plan view of one of the mechanisms used to compute the future position of the target along one coordinate at the time the shell strikes.

Fig. 6 is a side view of a complete computer as it appears to an observer.

Fig. 7 is a side view from the opposite side of the instrument.

Fig. 8 is an end view of the same.

Fig. 9 shows one of the lift cam mechanisms for introducing proper time of flight for range.

Fig. 10 is a diagram showing the mathematical principles involved and applicants' solution of the problem.

Fig. 10A is a simplified diagram showing the derivation of the equations used.

Fig. 11 shows one of the indicators that appears on the other end of the box, namely, the indicator showing the true course and speed of the target.

Fig. 12 is a detail thereof showing the holding mechanism for one cross hair.

Fig. 13 is another detail of the top plate which has been removed in Fig. 11.

Fig. 14 is a plan view, partly in section, of a series of cam followers used on the time of flight cams (see Fig. 9).

Fig. 15 is a detail of a portion of this mechanism combined with a simplified wiring diagram.

Fig. 16 is a vertical section through the contact mechanism connected therewith.

Fig. 17 is a diagrammatic view of the operating mechanism for one of the angle indicators. 5

Fig. 18 is a wiring diagram of the follow-up mechanism for parts of the computing mechanism.

Fig. 19 is a diagram used in explaining the 10 same.

Fig. 20 is a diagram showing a modified form of the invention.

Fig. 21 is a top plan view of a portion of the 15 plotting device.

The mathematical principles around which our computer is designed are based on what may be termed a circle diagram (see Fig. 10) in which a circle C is described to include both base stations B_1 — B_2 and the target T_0 . It is obvious that 20 a circle may always be drawn through any three given points. The distance between the base stations line B_2 — B_1 is, of course, known

($R_{B_2 B_1}$) 25

as is also the position of this line in azimuth, that is, the angle it makes with reference to the north-south line O, i. e.

$\angle A_{B_2 B_1}$ 30

The location of the battery DP is also known with respect to the base stations, this location being preferably defined by X and Y components from one or the other of the base stations, say 35 B_2 , the respective components being marked " X_{DP} " and " Y_{DP} ". The sighting telescopes in the base stations determine the sighting angles to the target, i. e. ϕ_1 and ϕ_2 . The triangle ($B_2 T_0 B_1$) thus formed within the circle of radius (r) contains an angle (ϕ_3) at the target (T_0) which is 40 used in the computations. A second angle (ϕ_4) at the center of the circle, formed by a line drawn through the center of the circle parallel to the base line and a radius (r) to the target (T_0), is 45 also used in the computations.

The radius (r) of the circle is combined trigonometrically with the sum (ϕ_4) or difference (ϕ_3) of the observed base end station angles (ϕ_2 and ϕ_1) to continuously obtain and indicate the linear 50 coordinates of the present position of the target. In some cases the range may be known

R_{B_2} or R_{B_1}

from one or the other base stations. From this 55 known data or a part thereof, the problem is to obtain automatically, without plotting boards or numerical calculations, all the necessary data to direct the fire at the target.

In Fig. 10 the following equations may be easily 60

demonstrated by plain geometric and trigonometric functions:

1. $\phi_3 = \phi_2 - \phi_1$
5. $\phi_4 = \phi_2 + \phi_1 - 90^\circ - 2A_{B_2B_1}$
3. $\phi = \phi_2 - A_{B_2B_1}$
10. $4. r = \frac{R_{B_2B_1}}{2 \sin \phi_3}$
5. $R_{x_0} = r \cos \phi_4$
6. $R_{y_0} = r (\sin \phi_4 + \cos \phi_3)$
15. $7. R_{x_{B_2}} = R_{B_2} \cos \phi$
8. $R_{y_{B_2}} = R_{B_2} \sin \phi = R_{y_0}$
20. $9. R_{x_0} = R_{x_{B_2}} - \frac{R_{B_2B_1}}{2} (\text{using } B_2)$
10. $10. R_{x_0} = R_{x_{B_1}} + \frac{R_{B_2B_1}}{2} (\text{using } B_1)$
25. $11. R_{x_p} = R_{x_0} + X_s + \frac{R_{B_2B_1}}{2} - X_{DP} + S_z t$
12. $R_{x_p} = R_p \cos A_{PB}$
13. $R_{y_p} = R_{y_0} + Y_s - Y_{DP} + S_y t = R_p \sin A_{PB}$
30. $14. R_{y_p} = R_p \sin A_{PB}$
15. $15. A_p = A_{B_2B_1} + A_{PB}$

Using the following nomenclature:

- B_2 and B_1 ----- Base end stations
 $R_{B_2B_1}$ ----- Base line length
 ϕ_2 and ϕ_1 ----- Base end station azimuths to target
 R_{B_2} and R_{B_1} ----- Base end station ranges to target
40 T_0 and T_p ----- Present and predicted target positions
 R_{x_0} and R_{y_0} ----- Present target position coordinates
 S ----- Target speed
45 t ----- Time of flight to predicted position
 S_x and S_y ----- Target component speeds
 S_t ----- Distance target moves on course in time " t "
50 $S_x t$ and $S_y t$ ----- Target coordinate setforward distances
 DP ----- Directing point or battery
 X_{DP} and Y_{DP} ----- Directing point coordinates
 R_{x_p} and R_{y_p} ----- Target predicted pos. coordinates from DP
55 R_p and A_p (A_{PB}) ----- Target predicted range and azimuth from DP
 $A_{B_2B_1}$ ----- True azimuth of base line
 E_r ----- Gun elevation for corrected range
60 T_c ----- Target course angle
 X_s ----- Spotter's correction along X axis
 Y_s ----- Spotter's correction along Y axis
65 The origin of the "X" coordinate

(R_{x_0})

may be taken at the mid point of the base line 70 length and at right angles to it, and the origin of the "Y" coordinate

(R_{y_0})

75 may be taken as the base line.

The derivation of the principal equations may readily be seen by reference to Fig. 10A. In this figure a circle of radius (r) has been constructed with the target T_0 and base end stations B_2 and B_1 in the circumference of the circlt. The 5 line from B_2 to B_1 is the baseline length

$R_{B_2B_1}$

The lines B_2T_0 and B_1T_0 are the lines of sight from the respective stations to the target. The 10 angle

$A_{B_2B_1}$

is the amount the base line is off the reference directional line (O). The line $a-a$ through the center (C) of the circle and the line $b-b$ through the target (T_0), are constructed as parallel to the base line

$R_{B_2B_1}$

The diameter $d-d$ through the center (C) of the circle is made perpendicular to the base line

$R_{B_2B_1}$

and bisects that line at its mid point (F), because 25 a radius which bisects an arc is perpendicular to the cord of that arc at its middle point. The line $e-e$ is parallel to the line $d-d$ and, therefore, is perpendicular to the lines B_2B_1 , $a-a$ and $b-b$.

Angle 1 equals angle 4 and angle 2 equals angle 3 30 as alternate-interior angles. Angle ϕ_3 is the difference between angles 4 and 3, therefore, angle ϕ_3 is also the difference between angles 1 and 2. Since the angle $A_{B_2B_1}$ is a common factor of both angles ϕ_2 and ϕ_1 , the following equation can 35 be written after substituting and equating:

$$(1) \quad \phi_3 = \phi_2 - \phi_1$$

Also, since an inscribed angle is measured by one-half its intercepted arc, angle 5 equals angle 40 ϕ_3 . In the right angle triangle B_2CF , angle 6 equals ninety degrees minus the angle ϕ_3 . In the isosceles triangle B_2T_0C , angles 7 and 8 are equal and, therefore, the angle 9 is equal to one hundred and eighty degrees minus twice the angle 7. Angle 7 is equal to one hundred and eighty degrees minus both angles 1 and 6. Angle 1 equals ϕ_2 minus angle $A_{B_2B_1}$. Angle ϕ_4 equals angle 9 plus angle 5 minus ninety degrees. The above equities may 50 be written in equation form as follows:

$$\begin{aligned} \angle 5 &= \phi_3 \\ \angle 6 &= 90^\circ - \phi_3 & \angle 1 &= \phi_2 - A_{B_2B_1} \\ \angle 9 &= 180^\circ - 2 \angle 7 & \angle 2 &= \phi_1 - A_{B_2B_1} \\ \angle 7 &= 180^\circ - \angle 1 - \angle 6 & \phi_4 &= \angle 9 + \angle 5 - 90^\circ \end{aligned} \quad 55$$

By substituting the first five equations into the last one, and simplifying, the result is as follows:

$$(2) \quad \phi_4 = \phi_2 + \phi_1 - 90^\circ - 2A_{B_2B_1} \quad 60$$

Again referring to Fig. 10A, the distance between the stations B_2 and B_1 is the base line length $R_{B_2B_1}$ but since the point (F) is the mid point of that line, the distance B_2F is one-half the base line length or

$\frac{R_{B_2B_1}}{2}$

The hypotenuse of the right angle triangle B_2CF is the radius (r) of the circle and the angle 5 is 70 equal to the angle ϕ_3 . The sine value of angle ϕ_3 is the distance

$\frac{R_{B_2B_1}}{2}$

divided by the distance r , or in equation form:—

$$(4) \quad r = \frac{R_{B_2 B_1}}{2 \sin \phi_3}$$

5 In the right angle triangle $T_0 C G$, the hypotenuse is the radius (r), therefore, the distance (R_{y_0}) can be obtained by employing the cosine function of the angle (ϕ_4), as in the following equation:—

$$10 (5) \quad R_{y_0} = r \cos \phi_4$$

The distance (R_{y_0}) is made up of two distances (R_{y_1}) and (R_{y_2}). In the triangle $T_0 C G$, the distance (R_{y_1}) can be obtained by employing the sine function of the angle (ϕ_4) as follows:—

$$15 \quad R_{y_1} = r \sin \phi_4$$

and in the right angle triangle $B_2 C F$ where the angle 5 is equal to angle ϕ_3 and the hypotenuse is the radius (r), the cosine function of angle (ϕ_3) is used to obtain (R_{y_2}):

$$20 \quad R_{y_2} = r \cos \phi_3$$

By the addition of the above value of (R_{y_1}) and 25 (R_{y_2}) the following equation results:—

$$25 (6) \quad R_{y_0} = r (\cos \phi_3 + \sin \phi_4)$$

The rates of change (S_x and S_y) (Fig. 10) of the coordinates R_{x_0} and R_{y_0} are component speeds 30 of the target and are preferably measured by variable speed drives and each rate is multiplied by the projectile's time of flight (t) to the predicted position (T_p) to obtain coordinate set-forward distances ($S_x t$ and $S_y t$). These coordinate 35 distances originating at the target are added algebraically with others to the matched present position coordinates to obtain the predicted or future position coordinates (R_{x_p} and R_{y_p}) of the target.

40 Provision is preferably also made to set in battery commander coordinate spots (which may be termed X_s and Y_s , but are not shown in the drawings), these distances also being added algebraically to the matched present position coordinates with their origin at the target (T_0).

45 The computer is preferably so constructed that there is no physical connection between the indicated present position coordinates and the matched present position coordinates. This allows the computer to continue to function on the basis of old data when an interruption occurs to the observed data. This condition holds for this system and the two others outlined below.

50 Since the future position coordinates are to be used to obtain the continuous setting of the gun azimuth (A_p) and gun range (R_p), the latter being converted into gun elevation (E_r) for that range by the computer, it is necessary to convert the algebraic sum of the above "X" coordinates 55 into another sum originating at the gun or directing point (D. P.) The left hand base end station (B_2) may be arbitrarily selected as the origin of the directing point coordinates (X_{DP} and Y_{DP}). To do this, we add an additional "X" factor, of the value of one half the base line length 60

$$65 \quad \left(\frac{R_{B_2 B_1}}{2} \right)$$

70 to the matched present position coordinate R_{x_p} , the algebraic sum of the above "Y" coordinates is unaffected by this shift.

$$75 (11) \quad R_{x_p} = R_{x_0} + S_x t + X_s + \frac{R_{B_2 B_1}}{2} - X_{DP}$$

$$13. \quad R_{y_p} = R_{y_0} - S_y t + Y_s - Y_{DP}$$

The future position coordinates, now originating at the directing point, form two sides of a right angle triangle with R_{x_p} as the base and R_{y_p} as the side at right angles to the base. The hypotenuse of the triangle is the gun range (R_p) to the future position of the target (T_p) and the angle (A_{pB}) that the hypotenuse makes with the base, when added to the base line azimuth ($A_{B_2 B_1}$) is the gun azimuth (A_p). In the above triangle the known quantities are R_{x_p} and R_{y_p} with R_p and A_{pB} as the unknowns. By the simultaneous solution of two equations, the continuous flow of range R_p and azimuth A_{pB} is obtained.

$$10 (12) \quad R_{x_p} = R_p \cos A_{pB}$$

$$14. \quad R_{y_p} = R_p \sin A_{pB}$$

$$15. \quad A_p = A_{B_2 B_1} + A_{pB}$$

The azimuth A_p is transmitted electrically to 20 receivers of the "follow-the-pointer" type, at the guns. Means is also preferably provided in the computer to set in azimuth deflections for spot and ballistic corrections.

The range R_p is matched by the lift of a cam 25 whose rotational factor is gun elevation (E_r). The range (R_p) is corrected for spot and ballistics by means of a "per-cent" range mechanism that applies range corrections to the generated range (R_p) before it is matched by the lift of the above 30 cam. The resulting gun elevation (E_r) is transmitted to the guns. Means is also provided for selection from multiple range-elevation and time-elevation cams when more than one powder charge or projectile weight is used or where the 35 computer is used for more than one type of gun.

The above method of tracking a target with two azimuth observing stations, one at each end of a measured base line, is commonly known as the horizontal base system of location.

40 Two other methods are provided for in our computer, one commonly known as the vertical base system and the other as airplane observation. These systems are used principally as alternatives in connection with the horizontal base system when the target cannot be seen simultaneously by two observing stations, as when some or all views are cut off by smoke screens, etc., or the target is over the horizon.

45 When using the vertical base system, one station continuously tracks the target in azimuth (ϕ) and sends its data to the computer in the same manner as was outlined above for the horizontal base system. In addition, this station measures the range (R_B) from it to the target, at regular time intervals, sending it to the computer. This range is set in and driven by a variable speed drive whose rate and value can be adjusted as each range is received.

50 The input of azimuth and range from the observing station is used to continuously generate and indicate the linear coordinates of the present position of the target with the origin of the "X" coordinate (R_{x_B}) at the station and the "Y" coordinate (R_{y_B}) origin as a base line to a second station. This set up is used so that a change 55 can be made to the horizontal base system when desired without interrupting the flow of predicted data to the guns.

$$60 (3) \quad \phi = \phi_2 - A_{B_2 B_1} \quad (\text{when using left hand station})$$

$$\phi = \phi_1 - A_{B_2 B_1} \quad (\text{when using right hand station})$$

$$7. \quad R_{x_B} = R_{B_2} \cos \phi$$

$$8. \quad R_{y_B} = R_{B_2} \sin \phi = R_{y_0}$$

It now becomes necessary to tie in the matched "X" coordinate (R_{XB}) with the horizontal base system coordinate (R_{x_0}) so that the above shift can be made. To do this it is only necessary to 5 shift the origin of R_{XB} , which is at its station (B_2 or B_1), to the mid point of the base line which is the origin of the horizontal base system R_{x_0} . If the left hand station B_2 is used, a minus (-) 10 value of one half the base line length is added to the matched R_{XB} . If the right hand station B_1 is used, a positive (+) value of one half the base line length is added to the matched R_{XB} .

15 9. $R_{x_0} = R_{XB_2} - \frac{R_{B_2B_1}}{2}$ (when using B_2)

10. $R_{x_0} = R_{XB} + \frac{R_{B_2B_1}}{2}$ (when using B_1)

20 The rates of change of the coordinates R_{XB} and R_{yB} are measured and used exactly as were those for R_{x_0} and R_{y_0} of the horizontal base system. From here on, the same means is employed 25 as was used for the horizontal base system to obtain continuous gun data. Under all solutions the length of the baseline $R_{B_2B_1}$ is, of course, known and also its direction in azimuth $A_{B_2B_1}$ which data is set in by locking handwheels 30 and 29, and the coordinates of the battery position 30 X_{DP} and Y_{DP} are also known and are set in by handles 32 and 33. Let us assume that there is transmitted to the computer the two target angles ϕ_1 and ϕ_2 . Our machine is set up then to 35 solve Equations 1, 2, 4, 5, 6, 11, 12, 13, and 15.

35 Referring first to Figs. 1A and 17 the azimuth angles may be received at the computer either by telephone at equal time intervals or by a synchronous electrical transmission system. The equal 40 time intervals are usually measured by the regular striking of bells in unison at the base end stations and at the computer. If done manually, the initial setting of the dial is accomplished 45 from the handle 11' which turns shaft 14 and also shaft 5' through differential 4, shaft 5' turning the dial 1 through the worm 5. An alternative drive for shaft 14 comprises a variable speed 50 drive including a sliding sleeve 13 splined to the shaft 14 and having thereon a large gear 313' and a small gear 313. In the position shown in Fig. 55 17, gear 313' meshes with a pinion 21' on shaft 21 for a slow speed drive from the latter, but by moving the change speed lever 13' upwardly to the first dotted position, gear 313 is brought into mesh with gear 21'' to drive said shaft 14 at a 60 higher speed. In still a third position, gear 313 is brought into mesh with gear 121 on shaft 12 of a power actuated device, hereinafter explained, thus providing a third drive for shaft 14.

60 The shaft 21 is shown as driven from a change speed device 16, 17 which may comprise a cylinder 17, a disc 18 continuously rotated from a constant speed motor 19, and a sliding ball or balls 16 which may be positioned axially on the cylinder and radially of the disc 18 by means of a rack 65 bar 16'. Said rack bar in turn is positioned by turning the rate handle 15 also connected to the rate indicating disc 15'.

70 After the initial angle is set in by rotating the handle 11', as explained, the gear shift lever 13' is set either into the position shown in full lines in Fig. 17 or the first dotted position depending on whether high or low speed transmission is desired but no motion takes place because at first the handle 15 is set to position dial 15' at 75 zero which positions the change speed controller

16 at the center of disc 18. Before the second reading is received, a second rate dial 15'' is set to zero against its index I by means of a knob 2'. Said dial and knob are frictionally mounted on shaft 315 driven from the shaft 3' of the handle 5 2 so that the dial 15'' normally turns with the shaft 3' but may be set independently. The second telephoned angle is set into the dial 1 by turning the handwheel 2 which drives the shaft 3', worm wheel 3 and differential 4 to turn shaft 10 5'. Turning the handwheel 2 displaces the rate dial 15'' relative to the index I by an amount equal to the change in angle between the first and second azimuth angle. This change, which is really also a rate of change because the time 15 intervals are known and constant, is immediately set into dial 15' by turning handle 15, thus setting the change speed device 16, 17 to drive the dial 1 at this rate through shaft 21 and 14. Indicator 15'' is then set back to zero. The third 20 and successive readings are set into the dial 1 in the same manner as the second reading with the exception of the reading of rate taken from the dial 15'' which is added to or subtracted from the original rate as the case may be. 25

Or a power multiplying system may be introduced to rotate the dial 1 as well as the dial 6 from the tower B_2 in which case hand setting is dispensed with. Said power system may be of any suitable form, such as shown, for instance, 30 in the copending application of Bruno A. Wittkuhns, now Patent No. 1,999,645, for Positional control of heavy objects, dated April 30, 1935 and assigned to the assignee of the present invention. It is represented in Figs. 1A and 17 as 35 comprising a motor 11 geared to shaft 12 and actuated through an amplifier 124 from the common A. C. supply S and the output of the transmitter-generator 1' and the polyphase transformer 1. When the power system is operating 40 45 the sliding gears 13 are shifted downwardly by handle 13' to engage the gear 313 thereon with gear 121 on shaft 12 so that the shaft 14 is turned to operate the dial 1 through the differential 4.

Still a third method of putting the angle ϕ_2 45 into the machine is by transmitting the angle by self-synchronous transmission from the base stations and turning the outer dial 6 from a repeater motor and merely matching the dials 1 and 6 by operating the handle 11'. In this case, 50 the handle 13' is moved to some intermediate position in which all gears are out of mesh and the motor 7 is merely used as self-synchronous repeater motor. By these means the angle may be set in the machine by any one of a plurality 55 of methods.

Similarly the angle ϕ_1 is set up upon the dial 24 by mechanism which may be identical to that for dial 1. Since from Equation 1, ϕ_3 is the difference between ϕ_2 and ϕ_1 , these two angles are 60 subtracted by differential 25 connected between shaft 26 driven from 1 and shaft 27 driven from 24, so that the output represented by the turning of the shafts 23 and 23' represents $\phi_2 - \phi_1$. From Equation 2 it should be noted that the sum 65 of these two angles is also employed so that at 25' is placed a second differential which adds these two angles, the result being transmitted to the shaft 27' through a differential 28 where the factor 2 70

$A_{B_2B_1}$

is introduced from the handwheel 29 which is set so that dial 29' shows the value of

$A_{B_2B_1}$

the 90° factor being taken care of by the set up of the gearing 66 and 28. Since this handwheel merely introduces a constant quantity for given base stations, it is first set and then locked during all subsequent operations of the machine on these two stations, this handwheel being one of a number of such locked handwheels. Other such locking handwheels are at 30, at which the length of the base is set in

10 $(R_{B_2 B_1})$

15 on dial 58, handwheel 32 introducing X_{DP} or the X component of the battery's position and handwheel 33 introducing Y_{DP} . It will be understood that each of these handwheels has a connected dial for setting the same.

20 The angle ϕ_3 represented by the rotation of the shaft 23' is introduced into the angle resolving mechanism 35 through the shaft 36 so as to position a slot 43 in a gear 42 at the angle ϕ_3 . The purpose of this unit is to solve Equation 4 for r , that is, the radius of the circle C, i. e.,

$$25 r = \frac{R_{B_2 B_1}}{2 \sin \phi_3}$$

30 Said instrument (Figs. 2 and 3) comprises a plurality of superimposed members comprising a bottom large gear 38 having a spiral slot therein 39 which is rotated from pinion 64 turned from the shaft 63 and setting handle 61. Above said spiral slotted gear is a second gear 42 which has therein said slot or transverse slideway 43 in which slides a block 44. Said gear is rotated from shaft 23' (ϕ_3) through shaft 36 and pinion 40. Said block 35 has a downwardly extending roller 45 thereon which engages said spiral. Said block also has an upwardly extending roller 46 thereon which engages a transverse trackway 47 in a rectilinear slide 48. Said slide is mounted for up and down movement at right angles to the slot 47 by rollers 49-50 (Figs. 2, 3 and 4) which roll along the opposite edges of fixed strip 49'. Said slide 48 is also guided at one side by slideway 50'. To said slide is secured a rack 51, the teeth of which engage a pinion 52 on a shaft 53. Preferably said pinion and shaft is journaled on an arm 54 pivoted at 55 on fixed bar 49' and is held against the rack teeth by the spring 56. Shaft 53 may carry at its outer end an indicator 57 forming a part of a follow-the-pointer indicator 58'' and which is arranged to match a pointer 258 which is turned from one of the locking handwheels 30 above described, namely, the handwheel which sets in the length of the baseline

55 $R_{B_2 B_1}$

60 and operated through worm 30'. The gears 38, 42, etc. are placed in a vertical position in the machine, the weight of the slide 48 being balanced by a counterweight 60 slidable in guideways 60'. It should be evident that if the gear 42 is positioned at angle ϕ_3 and if the gear 38 is positioned to move the rack up or downwardly a distance proportional to half the known base

65 $(R_{B_2 B_1}),$

then the mechanism will solve the equation

(1)
$$r = \frac{R_{B_2 B_1}}{2 \sin \phi_3}$$

70 In operation, after the locking handwheel 30 is set, the operator turns the handwheel 61 which rotates gear 38 through shaft 63 and pinion 64 until the pointer 57 matches the pointer 258 set from 30. This function may also be performed

automatically by providing a follow-up motor 26' to turn shaft 61' and actuated by follow-up contacts (not shown) on said indicator 58''. Differential 62 and pinion 62' meshing with 42 are provided to turn gears 38 and 42 together when 42 is turned so that the range setting will not be altered thereby.

75 The rotation of the shaft 61' is, therefore, a measure of r and may be introduced into the machine for solving some of the other equations. Firstly, it is introduced through differential 62' and shaft 63' into the calculating mechanism B which may be similar to calculating mechanism A except that it solves for the cosine of an angle instead of sine. We introduce into this mechanism the angle ϕ_4 from the shaft 66 so that Equation 5

$$R_{x_0} = r \cos \phi_4$$

is solved. Therefore, the x coordinate of the position of the target is located. This value is introduced by matching pointers 51' and 258', the former being positioned from the calculating mechanism and the latter from the handwheel 67 or other setting means.

20 The y coordinate is located by a pair of calculating machines C, the first of which has the angle ϕ_4 set up therein from shaft 66 and also r from shaft 61', thus giving one half of one part of Equation 6, namely, $r \sin \phi_4$. The second machine 30 has set up therein the angle ϕ_3 from shaft 23' and, therefore, solves for the $r \cos \phi_3$ portion of Equation 6. The two results are then added through differential 70 to rotate the pointer 71, the position of which, therefore, represents the y coordinate of the target position or R_y . This value 35 may be cranked into the machine by the handwheel 172 operating the follow-the-pointer indicator 71'.

40 Having located the coordinates of the present position of the target, we then proceed to locate the future position, which, of course, may be located by the coordinates of the present position plus (or minus) the distance moved thereby (during the time of flight of the shell) along the 45 course of the target, which may also be resolved into x and y components and algebraically added to the components of the present target position. For determining this position, we set up in the machine the rate of movement of the target in 50 each component direction (S_x and S_y) and multiply the same by the line of flight to give S_{xt} and S_{yt} . The x rate of movement is set in by the handwheel 172 and appears on dial 172'. This handwheel operates to position the change speed 55 element 73 of change speed gearing driven from constant speed motor 174 and similar to that above described.

55 As above explained, the handwheel 67 is turned to match the pointers 51' and 258' to give the 60 factor

$$R_{x_0}$$

65 It should be remembered, however, that the position of

$$R_{x_0}$$

70 is continually changing and, therefore, that pointer 51' is continually moving away from pointer 258' at a rate S_x . Therefore, by positioning the handwheel 172 so that the constant speed mechanism 73 introduces a rate of turn into the shaft 67' through differential 130, the matching of the two pointers may be maintained and a correct S_x set up. An auxiliary handwheel 131 may also be 75

provided for initial setting. The clutch 131' is used to disconnect the constant speed mechanism at that time.

A similar mechanism is provided for S_y comprising setting handle 72'' change speed gearing 73' which operates shaft 172' through differential 130'.

The S_x rate of movement is introduced into a computing unit E through the shaft 75 to turn threaded shaft 76 therein and thereby move a nut 77 (Figs. 1B and 5). Said nut has a pin 78 thereon engaging a slot 79 in a plate 80 secured to a disc 81. In said disc is a slideway 82 in which is slidably mounted a block (not shown) carrying a pin 83 projecting in both directions therefrom and similar to the block 44 of Fig. 2. Above said disc is mounted a cross bar 86 threaded at opposite ends in a pair of threaded shafts 87 and 87'. Said shafts are rotated in accordance with the time of flight of the shell (t) by means hereinafter described or by handwheel 187.

The downwardly projecting portion of the pin engages a transverse slot 84' in a slide 84 mounted for up and down movements on a slideway 88 by means of rollers 85 in a manner similar to the member 48 of Fig. 2. Slide 84 will be given a movement proportional to the product of S_x and t , or in other words, in proportion to S_{xt} , or the x component of the distance of T_p from T_0 . Similarly the y component is calculated from S_y and t by a calculator E' which may be identical to E, S_y being introduced through shaft 172'' to threaded shaft 76' and t through 87. This movement of the slide 84 (of the machine E) is transmitted by means of the rack bar 89 to a pinion 90 (Fig. 1B) where the value S_{xt} is added to other portions of Equation 11 through differential 88. Thus the hand setting 40 32 introduces X_{DP} or the X component of the gun's position, which is subtracted from $R_{B_2B_1}$ coming in through shaft 91 and gears 91' and 91'' to differential 92 and said combined factor is in turn added to R_{x0} through differential 93, the spotter's correction X_s being introduced from handwheel 120 through the differential 121 so that the rotation of shaft 94' represents R_{xp} or the x coordinate of the future position of the target from DP.

Similarly, Equation 13 is solved for R_{yp} by exactly similar mechanism as shown in Figs. 1B and 1C. Thus Y_{DP} is put in through the handwheel 33, the spotter's correction through handwheel 125 and the expressions R_{y0} and Y_{DP} are added and subtracted through the differentials 95 and 96 and S_{yt} introduced through differential 97 from rack bar 89' the final result, namely, R_{yp} , positioning the pointer 98 on indicator 99. Similarly, R_{xp} positions the indicator 98' on indicator 99'.

The factors that are wanted, however, are the range and bearing angle of the future position T_p of the target from the guns D_p which is shown in Fig. 10 as angle A_p or merely A_{PB} and distance R_p . These are obtained simultaneously from a pair of computing mechanisms D, in both of which are introduced A_{PB} and R_p . Said mechanisms may be similar to those previously described. Two setting handles are provided 100 and 101, from the one of which is derived the angle A_{PB} and from the other the range R_p , the two being interchangeable in operation.

The operators simultaneously turn handwheels 75 100 and 101 to obtain a matching of the two

pointers 102 with 98 and 102' with 98'. Or the matching may be obtained automatically through follow-up motors 100' and 101' controlled by contacts on instruments 99 and 99' respectively (see Fig. 18 described hereinafter). This cannot be accomplished except by turning the handwheels together as each handwheel effects both pointers, since in the two Equations 12 and 14 two unknowns are being solved. Handwheel 100 is shown as turning the shaft 103 through worm and wormwheel 104 and moves the radially slotted member 42'' of the calculating mechanism 105. In this instance the spiral disc 38'' is set from shaft 110 which, as will be observed, is turned from handwheel 101 through worm 111. The movement of the slide 48'', therefore, will be proportional to $R_p \sin A_{PB}$. In the other calculator 105', the angle A_{PB} is set in by means of shaft 112 geared to shaft 103 and R_p is set in from shaft 110 through differential 113 and shaft 114, thus positioning the slide 48''' to match pointers 102' and 98'. Since both pairs of pointers on indicators 99 and 99' are simultaneously matched, the two equations are simultaneously solved for the two unknowns R_p and angle A_p , the former appearing as the rotation of the shaft 110 on the dial 115 and the latter appearing as the rotation of the shaft 103' on the dial 116. The angle A_{PB} derived from the calculating units 105 and 105' driving shaft 103 passes through a differential 103'' before driving shaft 103'. In order to obtain the full angle A_p with reference to the orienting point O (see Fig. 10), the angle $A_{B_2B_1}$ is added to A_p by the differential 103'' being set into said differential by shafts 290 and handwheel 29 (Fig. 1A).

As shown in Figs. 6 and 7, the shafts of the handwheels 100 and 101 run straight through the machine, duplicate handwheels being on each side. On the other hand, the R_{y_p} indicator 99 is placed only on one side of the machine and the R_{x_p} indicator 99' only on the other side of the machine with one operator matching the X coordinates and the other the Y coordinates, both operations occurring simultaneously as above explained, but which handwheel (100 or 101) each operator employs depends upon the quadrant location of the target, because the operators in turning the handles are really converting the polar coordinates of range R_p and azimuthal bearings A_{PB} into rectilinear or X and Y coordinates. A consideration of the diagram shown in Fig. 19 will show that there are times when the observer of the R_{y_p} dial 99 should be operating the handwheel 100, that is the azimuth handwheel, and other times when he should be operating the range handwheel 101 and conversely with the observer of the R_{x_p} indicator 99'.

Thus, if the target is located at point T_1 in Fig. 19, it will readily be seen that a change in the angle A_{PB} is more effective in obtaining the coordinate R_{yp} than a change in the range R_p , while a change in the range R_p is more effective in obtaining the coordinate R_{xp} than a change in the angle A_{PB} . Similarly, if the target lies at the point T_2 it may readily be seen that a change in the angle is more effective in obtaining the X coordinate and a change in range is more effective in obtaining the Y coordinate. In other words, that somewhere between the points T_1 and T_2 the R_{yp} operator (observing indicator 99) should shift from handwheel 100 to 101 and vice versa with the R_{xp} operator.

In general, it may be stated that for target positions lying between 45° lines L and L_3 , the observer of the Y dial 99 should use handwheel 100 while the other observer uses the handwheel 101, while in the quadrant between 45° lines L and L_1 the reverse is true. Between quadrants L_1 and L_2 the same conditions prevail as between L and L_3 except that the signs are reversed, or, in other words, the handwheels have to be rotated in the opposite direction, while between L_2 and L_3 the conditions are similar to the conditions between L and L_1 except that the signs are reversed.

With manual operation the operators can be depended upon to shift handwheels at the proper time by their experience with the machine, but in case power follow-up system is employed, it is necessary to provide an automatic means for making this change-over. Such a means is shown in Fig. 18. According to this system, each of the indicators 99 and 99' are provided with trolleys 253 and 253' secured to rotate with the pointers 102 and 102' and the follow-up rings 252 and 252' secured to rotate with the follow-up pointers 98 and 98', respectively. Said contacts control the operation of the reversible power motors 100' and 101' through a series of relays R. For effecting the change-over control of the motors, we have shown a selector switch 261 which is laid out so as to transfer control near the 45° lines referred to in Fig. 19, a switch arm 262 being mounted on the shaft 104' of the handwheel 100. Said switch is provided with four contact sectors 1_1 , 1_2 , 1_3 and 1_4 . Each sector is preferably slightly greater than 90° so that there is an overlap of a few degrees adjoining each pair of sectors as indicated by the shaded sectors in Fig. 19. By means of interlocking relays R₁, the operation of which is well known in the electric motor control art and need not be described in detail, the control of the motors may be transferred and their direction reversed in accordance with the position of the switch arm 262 on the selector switches but within the overlapping regions the motor will remain in control of the contact sector first assuming control until the switch 262 leaves the same and rests only on the other sector. This is for the purpose of preventing rapid transfer of control of the motors in case the target is traveling near one of the 45° lines L.

Both shafts 103' and 110 are preferably connected to a data computer and transmitter of the form shown in our copending application, now Patent No. 1,999,368, dated April 30, 1935, where R_p or range is corrected by ballistics and spots (as percent range) and converted into E_r (gun elevation for corrected range). E_r is returned to the machine through the shaft 117 and appears on dial 117'.

The elements of this machine are shown in Fig. 1D. The range coming in through shaft 110 is transmitted through shaft 220, differential 221, shaft 222, gearing 222' and differential 223 to a follow-the-pointer or zero reader indicator 224. The duty of the operator of the handwheel 225 on shaft 225' (or the function of a follow-up turning the same) is to keep the indicator 224 reading zero. Turning of said handwheel operates the elevation shaft 117 and also the elevation transmitter 226. Its connection to the zero reader is through the differential 223 being turned in the opposite direction by the shaft 240 as follows. Turning of the handwheel 225 turns 75 through gearing 227 a shaft 228, on which is

mounted a series of range elevation cams 229. A plurality of cams are provided for different types of guns and powder charges, only one cam being used at a time. Cooperating with the same is a follower 230 which may be positioned over any one of the cams by turning the handwheel 231 which rotates the single toothed pinion 232 to move the rack 233 which carries the pin 230. Preferably the pin is lifted at the time it is shifted by the eccentric cam 234 which lifts block 235 and with it the pin whenever the toothed pinion 232 is rotated through a revolution. There may also be provided a high and low angle fire indicator 236 operated from a shaft 225' of handwheel 225 and from rack bar 233, as explained in the aforesaid application, and the name or number of such cam or zone as is being employed may be transmitted to the gun through "zone" transmitter 237 also driven from the rack bar 233.

The lift of the pin 230 is a measure of the range for any given elevation and this lift is shown as transmitted to the indicator 224 through the slide 238 resting thereon which has rack teeth cut thereon to turn the pinion 239 and thereby turn the shaft 240 and rotate the differential 223 to bring the indicator 224 back to zero. It is obvious that a power follow-up system may be employed for shaft 225' actuated from contacts on the indicator 224, if desired.

Range corrections may also be introduced by one or more handwheels 240 and 241. The handwheel 240 may be used to introduce spotting corrections as a percentage correction in range, while handwheel 241 may be used to introduce a ballistic correction also as a percentage range correction. These two corrections are combined through differential 242 to turn a threaded shaft 243 which moves laterally a lift pin 244. Said pin may have rack teeth thereon to turn a long cylindrical pinion 245 when the pin is lifted or lowered. Said pin may rest on a lever 246 pivoted at 247, which lever is positioned about its pivot by the lift of a pin 248 on an arbitrary percent range cam 249 turned from the shaft 110. The lift of pin 244 is, therefore, proportional to the percentage of the range selected by the correction handwheels and is transmitted as a proportional correction to shaft 222 through the differential 221.

The final target bearings A_p are shown as indicated on dial 250 and are transmitted through the azimuth transmitter 251 to the guns. The spotter's correction may be also introduced through a handwheel 252 through differential 253. Our computer, therefore, transmits to the guns all necessary data for firing, namely, the elevation, target bearings in azimuth and the zone employed.

The elevation as determined as above described is introduced into our computer by shaft 117. Said shaft positions a series of time of flight cams 118 which operate lift pins 119. Several cams are provided so that the machine may be used with guns of different characteristics. Five such cams 118, 118', etc. are shown in Fig. 14, but it will be understood that any desired number may be employed. A lift pin 119 is provided for each cam, each pin being mounted in a slide 140 which is slidably mounted in a framework 141 (Figs. 9, 14 and 16). At one side of the slides there is mounted a movable carriage 142 which may be moved up and down by the rotation of a threaded shaft 143. Said shaft is rotated from a follow-up motor 144 (see Fig. 1B) which rotates shaft 87 connected to screw shaft 143. Said motor is con-

trolled by a contact arm 145 pivoted on said carriage and adapted to make contacts 146 or 147 to operate said motor in opposite directions to raise and lower said carriage. Preferably contact arm 145 is made in the form of an angle bar pivoted at 148 to a second angle bar 149 which in turn is pivoted to the support 142 at 150. Both bars have their lower ends connected by springs 151 and 151' to the support so that the lower contact 147 is closed when the beveled knife edge 152 of arm 145 is pushed up, rotating arm 145 counter-clockwise (Fig. 16), the member 149 being held against the fixed stop 155 by the spring 151. Said edge is adapted to be engaged by a shoulder 153 on slide 140 so that as said slide moves down it tends to move away from said edge and spring 151' rotates the bar 145 clockwise to make the upper contact 146. The result is that carriage 142 is maintained in the same position with respect to the engaging end of the cam follower 119, which position is proportional to the time of flight of the shell, the latter being transmitted through the shaft 81 to the calculating mechanisms E and F for computing

25

S_xt and S_yt.

It should be noted that even though the follow-up mechanism fails, the contacts will not be damaged because if the carriage 142 is rising, for instance, and the motor fails to respond, the arm 145 will be bodily pushed to the left in Fig. 9 or 16 about pivot 150 as a center before any great pressure is exerted on the contact 147. It will be understood that a set of contacts is provided for each cam follower, but that only a selected one is used at a time to control the motor 144. This may be effected by leading one of the common wires through a push pin 201 which is plugged into one of a series of holes 202 corresponding to the cam desired to be used. It will be understood that the cam selected corresponds to the range elevation cam 229 used in Fig. 1D.

As above explained, our machine determines both the X and Y components of the course of the target, i. e. S_x and S_y. From these values a graphical representation of the target's course may be shown on the machine. Thus in Figs. 11 to 13 and in the lower left portion of Fig. 1C is shown such an indicator in which a horizontal cross hair 170 is positioned in accordance with S_y from an extension 175 of shaft 76' of machine E' or from handwheel 175', and a vertical cross hair 171 is positioned laterally in accordance with S_x either automatically or from handwheel 173 and the shaft or shafts 176 driven from shaft 76 of machine E. The cross hairs are stretched over nuts 278 threaded on said shafts and guided on trackways 278' and are held under tension by springs 279. Under said cross hairs are two rotatable dials, the outer one (178) of which is in the form of a ring having an index marked O thereon representing the angle

65

A_{B₂B₁}

and marked "target course". Said ring is rotated from shaft 179 set from the handwheel 29 through shafts 181 and 179'. Inner dial 184 represents the enemy ship or target 184' and has a fore and aft graduated center line 185 thereon. The circumference thereof is also graduated in degrees on which index O is read. This dial is turned from handwheel 186 so as to maintain the 75 intersection of the cross hairs 170 and 171 over

said center line 185. The angle, therefore, read on index O, is the true target's course T_c (Fig. 10) while the distance along the line 185 (Fig. 11), as shown by the graduations thereon, shows the actual speed S of the target, the component speed being shown by the linear graduations 189 and 190' on which the cross hairs 170 and 171 may be read.

Preferably we also design the machine so that the target may be located when one of the base stations cannot be used for any reason, such as, where the target is visible from only one station. According to this system the station in use (B₂ or B₁) continuously tracks the target in azimuth (ϕ) and sends its data to the computer in the same manner as outlined above. In addition, this station also measures range R_B from it to the target at regular time intervals sending this information also to the computer. This range is normally set in through a handwheel 132 (Fig. 1A) which positions the range dial 133 and turns the shaft 134. Preferably, as in the angle receiving mechanism, we also employ a variable speed device 16'' positioned by handwheel 134' so that the proper rate of change is set up in accordance with the received data. This input of azimuth angle and range from the observing station is used to continuously generate and indicate the linear coordinates of the present position of the target with the origin of the X coordinate R_{xB1} at the station and the Y coordinate R_{y0} origin as the baseline to the other station.

By reference to Fig. 10, it will readily be seen (using station B₂, for instance) that

$$(7) \quad R_{xB2} = R_{B2} \cos \phi$$

$$(8) \quad R_{yB2} = R_{B2} \sin \phi = R_{y0}$$

where

$$(3) \quad \phi = \phi_2 - A_{B_2B_1}$$

Equation (7) is solved by computing machine G into which range is introduced from shaft 134 to shaft 135 and ϕ is introduced from shaft 136 driven from shaft 137. Said shaft is adapted to be driven from either station ϕ_1 or ϕ_2 . In the former case, the clutch handle 138 is moved to the right and in the latter case to the left. The angle

$$A_{B_2B_1}$$

being set in through the handwheel 29, as above explained, is subtracted through the differential 153 so that the movement of shafts 137 and 136 represents the angle ϕ . Said mechanism G may be similar in all respects to mechanism B above described, the pointer or dial 154 indicating R_{xB}. Similarly, R_{yB} is computed from the computing mechanism H (Fig. 1B) into which is set the range R_B from the shaft 134 through shaft 135 and the angle ϕ through shaft 137 and 137'. The mechanism H solves Equation 8 so that the indicator 156 indicates the Y coordinate of target position which is also R_{y0} because the baseline B₂B₁ is taken as the origin of the Y coordinate in both systems.

The X coordinate, however, is taken from station B₂ (or B₁) instead of from the diameter d—d of the circle, as in the previously described system so that in order to utilize the mechanisms of the other system, it is necessary to transfer the X coordinate to the same origin. To do this it is only necessary to shift the origin of R_{xB} to the mid point of the baseline. If the

left hand station B_2 is used, one half the base is subtracted

$$\left(\frac{R_{B_2 B_1}}{2} \right)$$

5 while if the right hand station B_1 is used, this value is added (see Equations 9 and 10). To effect this purpose, the value $R_{B_2 B_1}$ is introduced through the handwheel 157 appearing on 10 the dial 158 and one half of this value is added or subtracted from R_{xB} through the differential 159. Both R_x and R_y having been obtained, these values are introduced into the machine for 15 solving Equations 11, 12 and 13 as explained above.

In some cases it may also be desirable to actually plot the course of the target. This may easily be effected in our machine since from the 20 values R_x and R_y obtained by either of the methods above described, a marker may be actuated to plot the course. Thus R_y may be put in from shaft 160 set in accordance with the reading of indicator 156 or 7' and which 25 may or may not be combined with spotting corrections Y_s introduced by handle 125. Shaft 160 is shown as operating through successive shafts 161, 161' and 162 and through a change speed gearing 163 to turn the threaded shaft 164 of 30 the plotting mechanism. Similarly, R_x (or $R_x + X_s$) may be introduced through change speed gearing 163' and shaft 165', which is turned from shaft 165 which in turn is turned from shaft 122 described above through gears 35 122', said shaft being turned either from shaft 159', turned from differential 159, or from differential 121, depending on whether the two-base station system or single-base station system is being used. The change speed gears 163 40 and 163' are merely for the purpose of changing the scale of the chart. The threaded shafts 164 and 164' are threaded through blocks 191 and 191', the former positioning the central sliding block 192 up and down on the chart along 45 rod 9 and the latter positioning the same laterally along rod 10, said rods passing through 90° bores or slots in the block. Secured to said block 192 is a marking arm 196 having a marker 197 at its outer end. A gear 195 is rotatably mounted on said block 192 and is turned about the center of intersection of said rods 9 and 10 50 by means of a worm 198 slidably but non-rotatably mounted on shaft 199 which is turned from bevel gear 200 slidably but non-rotatably mounted on shaft 201. Said shaft is positioned in accordance with the angle A_{PB} or, in other words, the future bearings of the target from the gun, this angle being obtained from computing mechanism D through shaft 202 and shaft 103. Therefore, the straight edge 195' of pantograph linkage 55 295 on member 192 is positioned at the correct gun angle and the line L drawn across the plot P of the target's course by means of said arm shows the angle of fire with reference to the ship's course.

60 Our machine is also adapted for use when the target is invisible from both base stations by using air plane observation. The observing airplane or other means sends in the bearing and 65 range from the target to some known terrestrial point. This information is preferably converted by plotting methods into R_x and R_y coordinates with reference to the pair of base stations intended to be used when the target becomes visible. These two values are then set into the

computer by the handwheels 67 (or 131) and 172 (or 212). The known terrestrial point as mentioned above may be taken as the station B_1 or B_2 and the observed ranges and bearings set into the computer by means of the dial 133 and (ϕ_1 5 or ϕ_2) respectively as was done for the single base end station method. The airplane also sends in the observed speed and course of the target which are also set into the machine as component speeds S_x and S_y so that the computer may generate the gun data from this data starting with Equation 11, the spotter's corrections X_s and Y_s also being put in from information sent from the aircraft.

10 By a slight modification, my invention is also 15 adapted for use where a target is zigzagging, that is, following a sinuous course. Referring to Fig. 20, the target is represented as first following a straight line course P and then zigzagging to avoid shell fire. Under such cases it becomes 20 impractical to set up component rates on account of their rapid change. Therefore, the operators of indicators 258' and 71' discontinue operating through the variable speed mechanisms 73 and 73' throw clutches 131' and 212' down and 25 turn the handles 131 and 212 which, in this instance, (Fig. 20) are also connected respectively through shafts 165' and 164' to threaded block 191' and through shafts 162' and 164 to threaded block 191. Therefore, block 192 and the recording pencil 197 will be moved in accordance with the observed course and speed of the target, thereby positioning the dial 184 so that the course and speed may also be read thereon as explained 30 above. During the zigzagging operation the operator turns the handwheel 186 which, in this instance, is connected through shafts 190, 202, 201 and 199 to turn the member 195 and thereby position the straight edge 195' tangent to the probable course a short distance ahead of the 35 present course, which thereby gives the heading of the target at the time the shell reaches the target. This setting of handwheel 186 also positions the line 185 on indicator 184 in accordance 40 with the ship's heading. Since the speed of the 45 ship may be assumed to remain substantially constant, the operator may then position the intersection of the cross hairs 170 and 170' so that the correct speed is shown on the line 185. This setting will then set into the machine the 50 S_x and S_y by reason of the fact that the shafts of the handwheels 173 and 175' remain connected as before to feed these rates back into the machine.

55 For the sake of simplicity, all dials and indicators are shown as single in the diagrams, but in the face views of the machine (Figs. 6, 7 and 8) most of them are shown as double, as a coarse and fine self-synchronous system is preferably used wherever possible.

60 In accordance with the provisions of the patent statutes, we have herein described the principle and operation of our invention, together with the apparatus which we now consider to represent 65 the best embodiment thereof, but we desire to have it understood that the apparatus shown is only illustrative and that the invention can be carried out by other means. Also, while it is designed to use the various features and elements in the combination and relations described, some of these may be altered and others omitted 70 without interfering with the more general results outlined, and the invention extends to such use.

Having described our invention, what we claim and desire to secure by Letters Patent is:

1. In a fire control computer, means for continuously introducing therein the bearings of the target from a pair of base stations, means for continuously computing therefrom and the known distance between said stations the coordinates of the present target position resolved along the line connecting said stations and perpendicular thereto including resolving units operating on the principle of a circle diagram containing the target and base stations, means for setting up therefrom the rate of change of target position along each coordinate, and means for computing from said change rates and the range the future coordinate target positions. 10
2. In a fire control computer, means for continuously introducing therein the bearings of the target from a pair of base stations, means for continuously computing therefrom and the known distance between said stations the coordinates of the present target position resolved along the line connecting said stations and perpendicular thereto including resolving units operating on the principle of a circle diagram containing the target and base stations, means for setting up therefrom the rate of change of target position along each coordinate, means for computing from said change rates and the range the future coordinate target positions, means for transferring the origin of said coordinates from a base station to the gun position, and means for re-converting said last-named coordinates into corrected target bearings and gun elevation from the gun position. 20
3. In a bearing fire control computer, means for continuously introducing therein the bearings of the target from a pair of base stations, means for computing therefrom the distance between said stations and the coordinates of the present target position from the center of a circle containing the target and base stations as the origin of the x coordinate and the cord connecting said stations as the origin of the y coordinates, means for computing the change of target position along each coordinate from the rate of change of the coordinates and time of flight of the shell to give predicted coordinate positions, means for transferring the origin of the coordinates to the gun position, and means for deriving the future ballistically corrected target bearings and gun elevation from the gun position from the last derived coordinates. 30
4. In a bearing computer, means for continuously introducing the target bearing and range from either of two base stations, means for computing therefrom the fixed rectilinear coordinates of the present target position from the selected station, said coordinates being parallel and perpendicular to the line connecting said base stations, means for computing change of target position along each coordinate from the rates of change of said coordinates and the time of flight of the shell to give predicted coordinate positions, means for transferring the origin of the coordinates to the gun position, and means for deriving the future ballistically corrected target bearings and gun elevation from the gun from the last derived coordinates. 40
5. In a bearing computer, means for continuously introducing either the bearings of the target from a pair of base stations or the bearing and range from one of said stations and the distance between said stations, means for deriving the linear coordinates of the target position from a base station from either data system, means for transferring the origins of the coordinates used to a common origin, common means for computing the change of target position along each coordinate from the rate of change of the coordinates and time of flight of the shell to give predicted coordinate positions, means for transferring the origin of the coordinates to the gun position, and means for deriving the future ballistically corrected target bearing and gun elevation from the gun from the last derived coordinates. 50
6. In a fire control computer, means for continuously introducing therein the bearings of the target from a pair of base stations, means for continuously computing therefrom and the known distance between said stations the coordinates of the present target position resolved along the line connecting said stations and perpendicular thereto including resolving units operating on the principle of a circle diagram containing the target and base stations, means for setting up therefrom the rate of change of target position along each coordinate, means for computing from said change rates and the range the future coordinate target positions, means for transferring the origin of said coordinates from a base station to the gun position, means for re-converting said last-named coordinates into corrected target bearings and gun elevation from the gun position, and means for introducing spotters range corrections as a percent correction in gun elevation. 60
7. In a fire control computer for predicting the range and bearings of a relatively moving target from a gun from continuously received bearing data from a pair of separated base stations, means for locating the present target position on the circumference of a circle also containing said base stations, means for resolving said position into x and y coordinates from a base station, means for setting up the rate of change of target position along each coordinate, means for computing from said rates and the time of flight of the shell the future coordinate target position, means for re-converting the last named coordinates into predicted target bearings and range from the gun position, and means for converting said range into gun elevation. 70
8. In a fire control director for a gun having a pair of spaced sights and in which the gun may be at neither sight, means for resolving the target's position as observed from both stations into rectilinear coordinates having as their origin the mid point of the cord line joining said sights, means for computing the rate of movement of the target along each coordinate, means for combining each rate with the time of flight of the shell to locate the predicted position of the target by its coordinates, and means for setting into said last-named means the components of the distance of the battery from said point of origin. 80
9. In a fire control director for a gun having a pair of spaced sights and in which the gun may be at neither sight, means for resolving the target's position as observed from at least one of said stations into rectilinear coordinates having said sight as the origin thereof and the line connecting said sights as the base, means for computing the rate of movement of the target along each coordinate, means for combining each rate with the time of flight of the shell to locate the predicted position of the target by its coordinates, and means for setting into said last-named means the components of the distance of the battery from said point of origin. 90

10. In a fire control computer, means for following the target's course along two component directions, means for setting up the component rates of said course, a course tracing device actuated from said last named means, a course and speed indicating dial having a course indicator actuated from said device, speed graduations on said indicator and component cross hairs readable on said graduations, means for estimating 10 the target's heading at a point preferably ahead of the traced course and setting said heading into said course indicator, and means for positioning said cross hairs on said dial to intersect said indicator at the target speed indication whereby the 15 component rates S_x and S_y are set into the computer.

11. In a fire control computer, means for following the target's course along two component directions, a course tracing device actuated from 10 said means, a course and speed indicating dial having a course indicator actuated therefrom, speed graduations on said indicator and component cross hairs readable on said graduations, a rotatable element on said device, a straight edge 15 connected thereto by parallel linkage, a common means for turning said element and indicator to position the straight edge tangent to the estimated trace, and means for positioning said cross hairs on said indicator to show the target speed

thereby setting component rates into the computer.

12. In a fire control computer, means for tracing to scale the path of the target from continuously supplied target bearings and range, whereby the future path may be estimated and drawn, a straight edge on said tracing means normally positioned tangent to the present course, means for positioning said straight edge tangent to a point in said future path, a target's course and speed indicating mechanism, means for feeding into the same the estimated future position of the target from said straight edge position, and means for resolving the future position so obtained into future rectilinear component target 15 positions.

13. In a fire control computer, a cam pin, a follow-up member, a lever pivoted on said member and adapted to be rocked by said cam pin and having two pairs of contacts operated thereby, a follow-up motor actuated in one direction or the other by closing of one or the other pair of said contacts and operating said member, and a pivoted link between said lever and said member whereby, in case said motor fails, said lever 20 is rocked about the link center out of the path of the pin.
